UNITED STATES PATENT OFFICE.

BYRON L. ZAERR, OF CHICAGO, ILLINOIS, AND CHARLEY W. HAMLIN, OF LOS ANGELES,
CALIFORNIA.

COIN-CONTROLLED STAMP OR TICKET VENDING MACHINE.

1,014,278.

Specification of Letters Patent.

Patented Jan. 9, 1912.

Application filed December 20, 1909. Serial No. 534,046.

To all whom it may concern:

Be it known that we, BYRON L. ZAERR, a citizen of the United States, residing at Chicago, in the county of Cook and State of Illinois, and CHARLEY W. HAMLIN, a citizen of the United States, residing at Los Angeles, county of Los Angeles, State of California, have invented a certain new and useful Improvement in Coin-Controlled Stamp or Ticket Vending Machines, and declare the following to be a full, clear, and exact description of the same, such as will enable others skilled in the art to which it pertains to make and use the same, reference being had to the accompanying drawings, which form a part of this specification.

Our invention has for one of its objects to produce a simple and novel apparatus for vending stamps, tickets, or other articles which may be rolled up and delivered by being unrolled from a reel or the like.

A further object of our invention is to produce a simple and novel controlling mechanism which will be caused to act selectively according as one or more coins or checks are dropped into it.

The various features of novelty whereby our invention is characterized will herein-after be pointed out with particularity in the claims; but, for a full understanding of our invention and of its various objects (including those enumerated and others) and advantages, reference may be had to the following detailed description taken in connection with the accompanying drawings, wherein—

Figure 1 is a front view of an apparatus arranged in accordance with a preferred form of our invention, the front wall of the casing being omitted and the door or shield for concealing the opening through which the articles are fed being shown in section. Fig. 2 is a section taken on line 2—2 of Fig. 1 looking in the direction of the arrows; Fig. 3, is a section taken on line 3—3 of Fig. 1; Fig. 4 is a section taken on line 4—4 of Fig. 1; Fig. 5 is a section on line 5—5 of Fig. 1; Fig. 6 is a transverse section on an enlarged scale showing the cover concealing the opening through which the stamps, or tickets are delivered and the knife which is actuated by this cover; Fig. 7 is a section taken at right angles to the actuating shaft showing the mutilated actuating gear and one of the clutch members; Fig. 8 is a view similar to Fig. 7 taken at

one side of the mutilated actuating gear, this gear being indicated in dotted lines; Fig. 9 is a section taken through the side wall of the casing and showing the cover member and the knife, the section being on line 9—9 of Fig. 10; Fig. 10 is a section taken on line 10—10 of Fig. 9; Fig. 11 is a vertical section through the rolls for feeding the stamps or tickets; Fig. 12 is a section taken at right angles to the main shaft adjacent to the locking cam for the knife; Fig. 13 is a section taken at right angles to the main shaft adjacent to the cam for releasing a controlling check; Fig. 14 is a view similar to Fig. 7, being taken, however, at a different point along the main shaft and showing the normal position of the clutch member; Fig. 15 is a view similar to Fig. 8, the clutch member being however, in position represented in Fig. 14; Fig. 16 is a view similar to Fig. 1, showing, however, only a fragment and illustrating a slot-closing device which may be employed; Fig. 17 is a view looking toward the right in Fig. 16; Fig. 18 is a plan view of the parts shown in Fig. 16; and Fig. 19 is a detail showing one of the controlling fingers.

Referring to the drawing, A represents a casing having a removable front wall A'.

B is a member which extends parallel with and is secured to the wall A' in any suitable manner as, by means of tie bars a^3 .

When the parts are assembled the casing is closed by the detachable wall and the member B lies within the casing. We prefer this arrangement since it permits all of the mechanism to be supported by or contained in either the detachable wall or the member B or both so that by removing one wall of the casing all of the mechanism may be removed so as to facilitate inspection and repair.

Our invention, in one of its aspects, is particularly designed for vending stamps, tickets, or other articles which may be wound or rolled upon a reel, sections of predetermined lengths being severed from the main body of the web upon the introduction of a coin or check and proper manipulation of handles or levers. In the arrangement shown provision is made for vending two different kinds of articles and, for the sake of brevity, we refer to these articles as one cent stamps and two cent stamps; it being of course understood that our invention is not limited to one which

will deliver only stamps of certain denominations or only two different kinds of stamps or other devices, but that instead of stamps any other articles which may be supplied in the form of a band or web may be employed and that the number of different kinds of articles may be varied as desired.

Journalized upon brackets C extending inwardly from the member B are a pair of revoluble reels D and D'. On the opposite side of the member B are feed rolls, there being a set of rolls E and E' corresponding to the reel D and a set of rolls E² and E³ corresponding to the reels D'. These feed rolls may be supported in any suitable way, there being in the arrangement shown brackets F F' and F² in which are journaled two shafts E⁴ and E⁵ on which are mounted respectively the rolls E and E²; and there being another set of brackets F³, F⁴ and F⁵ in which is journaled a shaft E⁶ on which are loosely mounted the rolls E' and E³. The web d from the reel D passes beneath the lower edge b of the member or wall B and between the rolls E and E'. The web d' extends similarly from the reel D' between the rolls E² and E³. In the wall A' of the casing is an elongated slot a directly in front of and parallel with the feed rolls. The mouth of this opening is preferably flared on the inner side as shown at a' so that the projecting ends of the webs will be guided in approaching the opening. Between the feed roll and the opening is an anvil G over which the webs are fed.

H is a knife which is adapted to coöperate with the anvil to shear sections from the ends of the webs.

40 By means of mechanism to be hereinafter described one or the other of the webs may be fed forward upon the insertion of a coin or coins a distance equal to the length of a single stamp, the parts being so adjusted 45 that the dividing line between two stamps is just at the cutting edge of the anvil. At this time the free end of the stamp projects through the opening so that it may be grasped by a purchaser. The knife is made 50 to descend and severs the stamp from the one which follows it.

We have shown the delivery opening closed by means of an oscillatory shield or cover I which normally drops by gravity 55 so as to conceal the opening. This shield or cover is so arranged that it will not interfere with the feeding of a stamp through the opening preparatory to cutting it off. The knife is connected to the cover in such 60 a way that when the cover is raised the knife is caused to descend so as to perform its cutting function. This connection may conveniently take the form of a rack h on the knife and a segmental gear i secured to 65 the cover and meshing with the rack.

In order to prevent extraction of a stamp without first depositing the requisite check or checks and also to prevent mutilation of a stamp through an attempt to withdraw it before it has been completely severed from the web, we prefer so to arrange the parts that neither the delivery opening or the projecting end of the stamp is exposed in whole or in part until the knife has moved to a position wherein it will have completely 70 severed a stamp if one has been fed outwardly for delivery. This may effectively be accomplished by arranging an outwardly projecting guard a² beneath the delivery opening and so shaping the shield or cover 75 that normally the lower end thereof underlies the guard. Normally the parts are illustrated in Fig. 1, the knife being raised slightly above the anvil. As the cover is lifted the knife begins to descend and, by 80 making the guard long enough, the cutting edge of the knife falls below the edge of the anvil before the lower edge of the shield or cover passes the outer edge of the guard. The final positions of these parts are indicated in Fig. 9. Consequently if no 85 stamp has been fed forward and the cover is lifted, the knife serves to close the delivery opening so as to prevent access to the web or webs; and, if a stamp has been delivered, the purchaser cannot take hold of it until it has been completely severed so that all danger of mutilation of the stamp 90 which has been delivered or those which follow is avoided.

If the knife were left free to be operated at any time it would be possible so to manipulate the cover that a stamp would be cut in two and therefore we have provided a lock which holds the knife against movement except after the feeding mechanism has fully fed a stamp forward. This may conveniently be accomplished by providing the knife with an opening h' into which a locking pin h² may project; this locking pin extending through the wall or member B and being provided with a spring h³ to retract it when free so to do. The opposite end of the locking pin projects into proximity to a cam disk K carried upon the main shaft L. The cam disk is provided with a notch k which is so positioned that when the main shaft is in its normal position the end of the locking pin may rest in the notch so as to leave the knife free to descend. The feeding mechanism is actuated from the shaft L in a manner which we will now describe.

The shaft L is revolvably supported in suitable bearings l and l' on one side of the member D and one end thereof is flattened as at L' so as to be received in a socket M' on the inner end of a crank shaft M, the crank shaft projecting through and being revolvably supported in one of the station- 125 130

ary walls of the casing. Upon the outer end of the crank shaft is a crank arm M^2 through which it is operated. M^3 is a spring associated with the crank shaft for holding it normally against a stationary stop M^4 . The socket M' and the end of the shaft L are so shaped that when the crank shaft occupies its normal position the main shaft will be disconnected from the crank shaft when the movable wall of the casing is taken out. It will be seen that the stationary stop not only maintains the crank arm normally in a predetermined position, but also limits the rotary movement thereof when it is actuated to operate the delivery mechanism. The notch in the cam member K is so placed that when the crank arm occupies its normal position the spring associated with the locking pin for the knife is free to retract the pin so as to release the knife, the knife being locked against movement at other times.

Mounted upon the main shaft and revolvable therewith is a mutilated gear N , this gear being adapted to mesh with a gear o carried by a rotary clutch member O mounted in and projecting on opposite sides of the wall B . Revolubly mounted at each end of the clutch member O are coöperating members with either of which it may be connected; these coöperating clutch members being indicated at O' and O^2 respectively. As will hereinafter be described, the member O may be locked to either of the coöperating clutch members by means of a proper coin or check. Each of the members O' and O^2 is provided with a gear, these being indicated at o' and o^2 . The gear o' is adapted to mesh with a gear e rigidly secured to the feed roll E while the gear o^2 is adapted to mesh with a similar gear e^2 connected with the roll E^2 . It will therefore be seen that if the main clutch member is clutched to the member O' and the crank is turned, the feed roll E will be rotated while the feed roll E^2 will remain stationary. The parts are so proportioned that when the crank is turned as far as it will go one or the other of the feed rolls will be rotated sufficiently to feed one of the webs a distance exactly equal to the length of a stamp. As soon as the crank is moved the locking pin is forced into engagement with the knife so that it is impossible to actuate the knife until the feeding of a stamp has been completed and it is therefore impossible to mutilate a stamp by working the knife too soon. In the arrangement shown the clutch member O is intended to oscillate back and forth through an angle of 180 degrees while the coöperating clutch members, of course, are continually rotated in the same direction. For this reason the gear N is made mutilated so that on the forward movement of the crank

it drives the main clutch member and then releases it so that the angle through which the feed rolls are rotated is not necessarily the same as the angle of movement of the crank. When the crank is released its spring returns it to the normal position and thereupon the teeth on the gear N again engage with the teeth on the clutch member and turn this member backward. In Figs. 14 and 15 the parts are shown in the normal positions before the crank is operated while in Figs. 7 and 8 the parts are shown in the positions which they assume when the crank is turned and before the return of the crank to its normal position.

We have shown means for driving only one member of each set of feed rolls and prefer this arrangement since it causes each stamp to be fed positively from one of the rolls, the other roll being arranged close enough to the driving roll to press the stamp against the driving roll; and, in order to make the drive more positive, a portion of each of the feed rolls may be roughened, as for example, by nurling as indicated at e^3 .

Normally the clutch members O' and O^2 are free from the main clutch member so that upon rotation of the crank no movement of the feed rolls occurs. It is intended that the main clutch member shall be connected to either of the coöperating clutch members by means of a coin or check of suitable size. In so far as the foregoing features of our invention are concerned these coins or checks may be brought into proper relation to the several clutch members in any suitable way. This may conveniently be done, however, in accordance with a second feature of our invention, that is, the peculiar construction and arrangement of parts whereby upon the insertion of one coin in a slot one of the feed rolls may be actuated, while upon the insertion of a second coin in the same slot the other set of rolls may be actuated. In one of the fixed walls of the casing, near the top thereof, is a coin slot a^4 , this slot lying adjacent to one edge of the member B . The member B may conveniently be made of two pieces, one piece B' containing the necessary passages or chutes and the other member, B^2 serving as a cover. The chutes are most clearly shown in Fig. 4, there being a main chute P whose outer end registers with the opening a^4 . The chute, after making a turn as indicated at p so as to absorb the shock of descending coin or check, leads directly to a point adjacent to the clutch members O and O^2 . Q is a socket one half of which is arranged within the clutch member O and the other half within the member O^2 , this socket, when the parts are in their normal positions of rest lying directly beneath the lower end of the chute and the size and the shape of the socket being such that it will easily receive a coin or check of the proper

size so as to cause the clutch members O and O^2 to be clutched together. P' is a branch chute which leads into proximity to the clutch members O and O' . When the parts are in their normal positions of rest the lower end of the chute P' is directly above a socket Q' similar to the socket Q , one half of the socket Q' being in the clutch member O and the other half in the clutch member O' . Thus it will be seen that when a coin or check is dropped into the socket Q' and the crank is turned the feed roll E will be operated while the other feed roll remains stationary. In the main chute below the turn p is a movable pin R which is adapted to arrest a coin or check at a point above the mouth of the chute P' . Leading from the main chute at a point somewhat above the pin R is a branch chute P^2 , this being so shaped and positioned that after the first coin or check has come to rest upon the pin R the next coin or check will ride over the first one and descend into the chute P^2 . Normally, if only a single coin or check is inserted and the pin R withdrawn, the coin or check will descend into the socket Q . If, however, a second coin or check be inserted before the pin is removed such second coin or check will strike a swinging gate S which projects into the chute P^2 and through its weight will force the gate laterally. The gate S is connected to a gate or deflector S' which is arranged at the mouth of the chute P' and which is adapted to serve as a selecting device to cause a coin or check resting upon the pin R to drop either into the socket Q or the socket Q' . The members S and S' may conveniently be joined together by means of a link S^2 , there being a spring S^3 which engages with this link and serves to hold the members S and S' in the positions wherein the mouth of the chute P' is closed. When a coin or check strikes the gate S and forces it laterally, a corresponding movement is imparted to the deflector and it is swung across the lower leg of the main chute so as to direct a descending coin or check into the chute P' and thence into the socket Q' . T is a movable stop arranged so as to project into the chute P^2 in proximity to the swinging gate and serving to support the second coin or check in a position wherein it holds the gate retracted and the deflector S' swung across the lower leg of the main chute. It will thus be seen that if a single coin or check is dropped into the slot and the supporting pin R removed the main clutch member will be connected to the clutch member O^2 . If, however, a second coin is deposited before the pin R is withdrawn then, upon withdrawal of the latter pin, the check will descend into the socket Q' so as to connect the main clutch member to the member O' .

65 Where the apparatus is intended to vend

one cent stamps and two cent stamps, the dropping of a single one cent into the slot will secure the delivery of a one cent stamp while, upon the insertion of two cents, a two cent stamp will be delivered. The stops or 70 rests R and T are provided so as to maintain the selective apparatus in the proper position until the crank is turned, thereby insuring that the proper selection will be made and preventing the apparatus from 75 being clogged with coins. The stop T is connected to a swing gate U in the chute P' by a link or rod T' . T^2 is a spring which serves to hold the member T in its operative position. The gate U is so positioned that 80 it is engaged by a coin or check descending the chute P' and is oscillated thereby sufficiently to withdraw the member T from beneath the coin or check in the chute P^2 . Consequently before the one coin or check 85 drops into the clutch socket, the other has released and leaves the chute. The chute P^2 is extended toward the bottom of the casing so that the coins or checks passing there-through drop into a free space in the bottom of the casing. Directly beneath the clutch members are chutes P^3 and P^4 which are adapted to register with the sockets Q and Q' respectively when the clutch members are rotated through an angle of 90 95 degrees. These latter chutes also lead into the bottom of the casing so that after a coin or check has served to connect two of the clutch members together and a feeding operation has taken place, it drops into the bottom of the casing and leaves the apparatus clear to receive further coins or checks.

As we have heretofore seen the clutch members O' and O^2 are intended to be rotated continually in one direction, while the 105 clutch member O is intended to be oscillatory. Consequently each of the clutch members O' and O^2 is provided with two diametrically opposed half sockets Q^3 so that, after a half revolution of either of these 110 clutch members, there remains a half socket on the upper side which, with the corresponding half socket on the main clutch member, forms a complete socket upon the 115 return of the main member to its normal position.

In order to insure the stopping of the main clutch member in the proper positions at the limits of its movements we have provided it with a projecting lug o^5 which is 120 adapted to pass through slots b^5 and b^6 in the member B' and to strike against the side of the member B^2 . It will therefore be seen that if the momentum of the main clutch member should be enough to carry it past 125 its proper position when moving either direction, the engagement of the lug with the stationary wall member will prevent such movement.

It may at times happen that after the 130

clutches have been turned half revolution so as to bring the coins or checks over the discharge chutes, the coins or checks will stick in their sockets instead of falling 5 therefrom. We have therefore provided means for positively ejecting the coins or checks after the clutch members have been turned so as to bring them over the discharge chutes. In the arrangement shown 10 this means consists of fingers V pivotally supported upon a bracket V' and extending into the spaces between the clutch members. An arm V² projects from these fingers into proximity to the gear N and on this gear is 15 a pin n which is adapted to strike the arm. The normal position of the parts is that indicated in Fig. 15, a check W having just been received in the socket between two of the clutch members. During the operation 20 of the mechanism that is, upon turning the crank, the gear member N turns in the direction of the arrow and after the clutch members have completed their forward movement the pin n engages with the rear 25 side of the arm V² as indicated in Fig. 8, thereby swinging the fingers V downwardly so that one of them engages with the upper edge of the coin or check and forces it out of the socket. As soon as the crank arm re- 30 turns to its normal position, the weight of the arm V² causes it to swing downwardly and thereby lift the fingers out of the path of a coin or check in one of the sockets.

We prefer to maintain the first coin or 35 check in its elevated position until the crank is turned and to this end we arrange upon the main shaft a cam disk X which engages with the lower end of a lever Y pivotally mounted upon the member B and connected 40 at its upper end to the pin R. This cam is so shaped that when the crank is in its normal position the cam is just ready to withdraw the pin. The raised portion X of the cam extends through a considerable arc so 45 as to give the coin or check ample time to drop before the pin again projects into the slot; but, as soon as the end of the lever drops from the high portion of the cam, the pin again projects across the slot so that 50 another coin or check may be inserted im- mediately without producing any disarrangement of the mechanism. In order to permit the pin R to be withdrawn before the main clutch member is moved we prefer 55 so to locate the teeth n' on the gear wheel N that they do not engage with the teeth on the main clutch member until after the crank has moved through an angle sufficient to permit the high portion of the cam X to 60 come in contact with the end of the lever controlling the pin R.

In order to make it easier for the knife to sever the stamps we prefer to make the cutting edges thereof h⁵ and h⁶ inclined so that

upon the descent of the knife a gradual 65 shearing takes place.

In Figs. 16 to 19 we have shown an arrangement which may be employed to close the chute against entrance of a coin in case one of the webs breaks or the supply of material is exhausted. This may conveniently consist of a swinging door or gate Z adapted to swing across the mouth of the chute P. This member is connected by means of a rod Z' to an arm Z² of a rock shaft Z³ which lies 70 below those portions of the webs between the member B and the feed rolls. On this shaft are arranged a number of fingers Z⁴ which are arranged so as to have a limited angular movement about the axis of the shaft inde- 75 pendently of the shaft. The parts are so adjusted that these fingers overlie the webs and hold the gate or door in position shown in Fig. 16. In case one of the webs should break, one of the springs Z⁵ associated with 80 said fingers would come into play and positively rotate the shaft sufficiently to close the entrance to the chute. In order to make the closing device operate when the stamp supply is exhausted, the ends of the webs 85 may be secured to the reels by means of narrow strips Z⁶, these strips being made narrow enough that they will clear the fingers and thus permit the latter to act after the 90 last stamp has been withdrawn.

While we have illustrated and described with great particularity only a single preferred form of our invention we do not desire to be limited to this single form, but intend to cover all constructions and arrangements which fall within the terms employed in the definitions of our invention constituting the appended claims.

What we claim is;

1. In a check-controlled apparatus, a member having a check-receiving chute, a plurality of controlling devices, selective means for bringing a check in said chute into operative relation to any one of said devices, means for resting the aforesaid check while it remains in said chute and means controlled by another check entering said chute while the first check remains in the chute for governing said selective means.

2. In a check-controlled apparatus, a member having a check-receiving chute, two controlling devices, a selective device for directing a check in said chute toward either of said devices, means for resting the aforesaid check while it remains in said chute and means controlled by a second check entering said chute while the first check remains in the chute for governing said selective device.

3. In a check-controlled apparatus, a member having a main check-receiving chute and two branch chutes leading from the main chute, a selective device for directing a check from the main chute into either of the

branch chutes, means for resting the aforesaid check while it remains in said chute and means governed by another check entering the main chute while the first check 5 remains in the chute for controlling said selective device.

4. In a check-controlled apparatus, a member having a check-receiving chute, there being two paths for a check leading from 10 said chute, selective means for determining which of said paths a check in said chute shall follow, means for resting the aforesaid check while it remains in said chute and means controlled by another check entering 15 said chute while the first check remains in the chute for controlling said selective means.

5. In a check-controlled apparatus, a member having a check-receiving chute, a deflector for determining the direction of a check 20 entering said chute, means for resting the aforesaid check while it remains in said chute and means controlled by a second check entering said chute while the first check remains in the chute for actuating said deflector. 25

6. In a check-controlled apparatus, a member having a check-receiving chute, a movable stop in said chute for arresting a check, there being a plurality of paths for said 30 check after passing said stop, a selective device for determining the path which said check shall follow, and means controlled by a second check entering said chute while the first check remains in the chute for controlling said selective device. 35

7. In a check-controlled apparatus, a member having a check-receiving chute, a movable stop in said chute for arresting a check, said chute being divided into two branches 40 below said stop, a device for directing said check into either of said branches and means controlled by a second check entering said chute while the first check remains in the chute for controlling said device. 45

8. In a check-controlled apparatus, a member having a main check-receiving chute, a movable stop in said chute for arresting a check, said chute being divided into two branches below said stop, a device for directing said check into either of said branches, there being an auxiliary chute leading from the main chute at a point above said stop, and a controlling member for said device in said auxiliary chute in a position to be 55 engaged by a coin entering the auxiliary chute.

9. In a check-controlled apparatus, a member having a main check-receiving chute, a movable stop in said chute for arresting a 60 check, there being two paths for said check below said stop, a selective device for determining which path said check shall follow an auxiliary chute leading from the main chute at a point somewhat above said stop, and a controlling member for said device 65

located in the auxiliary chute in position to be engaged by a check entering the auxiliary chute.

10. In a check-controlled apparatus, a member having a main check-receiving chute, a movable stop in said chute for arresting a check, there being two paths for said check below said stop, a selective device for determining which path said check shall follow an auxiliary chute leading from the main chute at a point somewhat above said stop, a controlling member for said device located in the auxiliary chute in position to be engaged by a check entering the auxiliary chute, a stop in the auxiliary chute for arresting a check in engagement with said controlling member, and means for actuating said stops. 80

11. In a check-controlled apparatus, a member having a main check-receiving chute, a movable stop in said chute for arresting a check, there being two paths for said check below said stop, a selective device for determining which path said check shall follow an auxiliary chute leading from the main chute at a point somewhat above said stop, a controlling member for said device located in the auxiliary chute in position to be engaged by a check entering the auxiliary chute, a feeding device, actuating means for said feeding device, and a connection between said actuating means and said stop for controlling the stop. 90

12. In a check-controlled apparatus, a member having a check-receiving chute, two feeding devices, an actuating member, constructed and arranged to be connected to either of said devices by a check, a selective device for directing a check in said chute so as to connect said actuating member to either 100 of said feeding devices, and means controlled by a second check entering said chute for controlling said selective device. 105

13. In a check-controlled apparatus, a member having a check-receiving chute, two feeding devices, an actuating member, constructed and arranged to be connected to either of said devices by a check, a selective device for directing a check in said chute so as to connect said actuating member to either 110 of said feeding devices, a movable stop for arresting said check before it reaches said selective device, and means controlled by a second check entering said chute for controlling said selective device. 115

14. In a check-controlled apparatus, a member having a check-receiving chute, two feeding devices, an actuating member, constructed and arranged to be connected to either of said devices by a check, a selective device for directing a check in said chute so as to connect said actuating member to either 125 of said feeding devices, a movable stop for arresting said check before it reaches said selective device, means con- 130

trolled by a second check entering said chute for controlling said selective device, a movable stop for arresting said second check in operative relation to said means, and operating means for said stops and said actuating device.

15. In a check-controlled apparatus, a member having a check-receiving chute, a plurality of controlling devices, a selective device for directing a check in said chute toward either of said devices, a movable stop for arresting said check before it reaches said selective device, a controlling member for said selective device arranged in the path of a second check entering said chute, a movable stop for arresting said second check in operative relation to said controlling member, and means for actuating said stops in succession.
16. In a check-controlled apparatus, a member having a check-receiving chute, a movable stop for arresting a check in said chute, there being two paths for such check below said stop, a selective device for determining which of said paths the check shall follow, a controlling member for said selective device arranged to be engaged by a second check entering said chute, a second movable stop for arresting the second check in operative relation to said controlling member, and an actuating device for said second stop lying in one of the aforesaid paths in position to be engaged by the first check when traveling along that path.
17. In a check-controlled apparatus, a member having a check-receiving chute, independent delivery mechanisms, an actuating element, check-controlled clutches between said element and said mechanism, a movable stop for arresting a check in said chute, separate paths leading from a point in said chute below said stop to said clutches, a selective device for determining which of said paths the aforesaid check shall follow, a controlling device for said selective device in the path of a second check entering said chute, and a connection between said actuating element and said stop for moving the stop to release the first check.
18. In a check-controlled apparatus, a member having a check-receiving chute, independent delivery mechanisms, an actuating element, check-controlled clutches between said element and said mechanism, a movable stop for arresting a check in said chute, separate paths leading from a point in said chute below said stop to said clutches, a selective device for determining which of said paths the aforesaid check shall follow, a controlling device for said selective device in the path of a second check entering said chute, a second movable stop for arrest-

ing the second check in operative relation to said controlling device, an actuating member for said second stop arranged in proximity to one of the first mentioned paths so as to be engaged by the first check when traveling along that path, and a connection between said actuating element and said stop for moving the stop to release the first check.

19. In a check-controlled apparatus, a casing having a check-receiving chute, two feeding members, independent driven members each geared to one of said feeding members, a driving member, said driving member and said driven members having slots to receive checks so as to connect the driving member to either driven member, a movable stop for arresting a check in said chute, said chute being divided into two branches below said stop each branch leading toward one of said driven members, a selective device for determining which of said branches a check shall follow, a controlling member for said device arranged in the path of a second check entering said chute, and means associated with said driving member for moving said stop.

20. In a check-controlled vending apparatus, a casing, a removable wall on said casing, a member carried by said wall and containing check-receiving chutes, and feeding and delivering apparatus mounted on said movable wall and upon said member.

21. In a check-controlled vending apparatus, a casing, a removable wall on said casing, a member carried by said wall and containing check-receiving chutes, and feeding and delivering apparatus mounted on said movable wall and upon said member, an actuating member on a fixed portion of said casing, and a driving connection between said actuating member and said feeding and delivery apparatus arranged to permit the parts to be disengaged by a relative lateral movement parallel with the direction of movement of said movable wall.

22. In a check-controlled apparatus, a member having a check-receiving chute, a plurality of controlling devices, selective means for bringing a check in said chute into operative relation to one of said devices, means for resting a check in advance of said selective means, and means controlled by another check for governing said selective means.

In testimony whereof, we sign this specification in the presence of two witnesses.

BYRON L. ZAERR.

CHARLEY W. HAMLIN.
